UNITED STATES PATENT OFFICE.

JOHN J. C. SMITH AND VICTOR E. SMITH, OF PASSAIC, NEW JERSEY; SAID
JOHN J. C. SMITH ASSIGNOR TO SAID VICTOR E. SMITH.

APPARATUS FOR CASTING METALS.

SPECIFICATION forming part of Letters Patent No. 477,231, dated June 21, 1892.

Application filed April 28, 1891. Serial No. 390,729. (No model.)

To all whom it may concern:

Be it known that we, JOHN J. C. SMITH and VICTOR E. SMITH, citizens of the United States, residing at Passaic, in the county of Passaic 5 and State of New Jersey, have jointly invented new and useful Improvements in Apparatus for Casting Metals, of which the following is a specification.

The invention relates to a means of producing very light and thin metallic castings, more especially such as are marked with elaborate designs, with a sharpness and perfection equal to electro-deposits.

Our invention is an improvement on those methods of and apparatus for metallic casting in which effective penetration of the fluid mass to and intimate contact with every part of the matrix is sought to be secured by, first, collection and temporary detention of the entire charge of molten metal in a suitable holder above the molds; secondly, prompt, rapid, and continuous transfer of the purely-metallic portions of the entire body of molten metal from the bottom of such holder to the 25 matrix-cavities, leaving impurities in the sprue; thirdly, the twofold operation of increasing the pressure at the rear and diminishing the pressure in front of the advancing stream of molten metal.

30 The products of our invention are greatly superior to any known to us except those of the comparatively costly expedients of original engraving or of electroplating.

The scope and character of our improvement will be better understood after a brief reference to the state of the art.

For many years past it has been the aim of workers in metal to produce, by means of the comparatively cheap process of casting, metallic articles of slight thickness and elaborate design, such as have heretofore been produced either by the costly expedient of electroplating or by the still more expensive labor of the engraver.

45 While our present invention is applicable to founding or casting operations generally, it has more particular reference to where it is not only essential to have perfectly sharp and finished outlines of the most minute ornamental details, but also to combine therewith

a required lightness of weight and economy of material—such, for example, as called for in the endless variety of table-ware, toilet articles, medallions, and other delicate metallic objects of use, ornamentation, and luxury. 55 Like articles are usually manufactured out of sheet metal, either by spinning against a pattern or by stamping or hammering in dies. These processes do not transfer the finer details of the design, which consequently have 60 to be added by the skilled labor of the chaser or engraver.

The object of our invention is to produce perfect castings in the most refractory metals—such, for example, as German silver—of 65 any required thinness and with a faithful reproduction of the most elaborate ornamental details. The molds for these fine, delicate, and sharp castings are preferably made of clay pressed on a pattern and then baked 70 after the manner set forth in Letters Patent No. 70,038, granted to Michael Smith October 22, 1867. An apparatus is needed by means of which the metal collected in a convenient cylinder can be injected almost instantaneously to every part of the matrix-spaces. 75 This purpose is accomplished by applying suction, which absorbs and carries away the air and gases from the matrix-spaces through the substance of the said baked-clay 80 molds, while, on the other hand, pressure is applied to expedite the entrance of the metal and its prompt and effective permeation to every part of said spaces. Furthermore, it is requisite that the molds be so effectually 85 sealed and clamped that escape of metal from the matrix-spaces is avoided.

Referring to the accompanying drawings, which form a part of this specification, Figure I is a perspective view of a casting apparatus adapted to carry out our said method. Fig. II is a vertical longitudinal section of such apparatus in its closed condition, the charging-cylinder being shown in act of receiving its charge of metal. Fig. III is a like 90 cylinder taken at a later stage in the operation, the pressure of the forming-piston having broken through the asbestos diaphragm, thus allowing the metal to pass through the gate into the matrix-spaces, communication 95 100

having been previously opened from the outside of the molds to the vacuum-chamber. Fig. IV is an end view of the apparatus in a partly-open condition. Fig. V represents a pair of molds detached. Fig. VI is a diagrammatic projection of the casting apparatus and vacuum-chamber.

The apparatus comprises the following principal parts: The base of the apparatus 10 consists of an air-tight supporting and exhaust box 1 of somewhat greater length and width than the molds. On this box are stacked the molds 2, their matrix-spaces 3 communicating by channels 4 with vertical orifices, 15 which constitute the gatings 5. The molds 2 are preferably of such finely-porous material as unglazed earthenware or plaster-of-paris, and fit each other and the casing-floor with sufficient exactness to prevent intrusion of 20 molten metal between the partings without obstructing the escape of air, vapor, and gases. Upon the stack of molds is placed a coping or platen 6, which has an orifice 6' in line with the gatings 5. The extremity of the box 25 1, remote from the orifice 6', communicates by orifice 1' with the interior of the mold-case, and by pipe 7, having a stop-cock 7', with a vacuum-chamber 8 of considerably larger capacity than said box. The pressure in this 30 chamber may be lowered to the required approximate vacuum by any suitable means—for example, by a steam-operated ejector 9. Secured to the top of the said coping 6 is a circular elevation or disk 11, having an orifice 11' 35 immediately over the orifice 6'. Upon disk 11 is placed a circular mat or diaphragm 12, of asbestos, of slightly greater diameter than said disk. The disk 11 with its mat 12 constitutes the floor or bottom of a forcing, injecting, or charging hopper or cylinder 13, which, 40 being fastened to the coping by screws 13', its rabbet 14' fits tightly over and clamps the projecting margin of the said asbestos mat, which is thus made to do duty as a luting or 45 gasket. The said mat also, for the time being, closes the passage from the said charging-cylinder into the gatings 5, and thus temporarily prevents entrance of metal to the molds. (See Fig. II.) With this object in 50 view the mat is of sufficient consistence and thickness to resist rupture by the mere weight of molten metal in the cylinder. 14 is a scupper or runner which conducts the molten metal into the said charging-cylinder. From 55 the mat 12 upward to within a short distance of its rim the walls of the said cylinder are lined with a tube 15 of like asbestos matting. This asbestos tube discharges a triple function, namely: It serves by its refractory and 60 non-conducting qualities to conserve the heat of the molten metal, and at the same time to prevent adherence of the latter to the said walls, and as a luting to prevent escape of the metal past and adherence of same to the forcing-piston now to be described.

Fitted to slide snugly but freely in cylinder

13 is the forcing-piston 16, which may be elevated and depressed by any suitable device. For example, the rod of said piston may be a rack 17, into which gears a cogged segment 18, having a lever or operating-handle 19. The rack-rod 17 is guided and the cogged segment 18 is journaled in a suitable standard 20, which extends vertically from the coping. Secured to the box 1 by hinges 21' are four 75 side boards 21, which, being secured to the vertical position shown in Figs. I, II, and III by screws 21' or other fastenings, constitute a flask or casing, which surrounds the stack of molds at sufficient distance therefrom to afford room for a tamping 22 of compact loam up to the level of the top of the coping. Secured to the ends of the box 1 by hinges 23' are yokes or straps 23, tapped, within which are screws 24, which enable the coping to be 85 forced down firmly upon the mold.

25 is an asbestos facing for the piston 16. This asbestos facing coacts with the asbestos tube 15 and the mat 12 to prevent either chilling or adhesion of the metal, and the said disk and tube co-operate to hermetically close or pack the cylinder against upward escape of the molten metal; the accumulating body of asbestos increasing and becoming compacted in proportion to the forcing-pressure. 90 A tube or bushing 26 of asbestos, which lines the passage from the cylinder to the gatings, completes the provisions for preventing contact of the molten mass with any metallic surfaces.

An eye or ring 27 enables the removal and replacement of the platen with its associated forcing mechanism through the instrumentality of a suitable crane 28.

The effectiveness of the above-described 105 method and apparatus for the formation of extremely light and sharp castings having a solidity, homogeneousness, and a freedom from blow-holes comparable to electro deposited or to rolled metal is largely attributable to, first, 110 the absolute isolation of the molten mass from metallic surfaces; second, the disconnection of the molten mass from the molds until the instant of inflow; third, the effective removal of air, vapor, and gases from the 115 matrix-spaces and the pores of the molds prior to and during the inflow by communication with a large and continuously-exhausted vacuum-chamber; fourth, the complete hermetical sealing in of the molten metal from 120 the instant of the application of the forcing-piston.

The above-described illustration of our casting apparatus is susceptible of various modifications. For example, the bottom of the 125 mold-casing may be a solid plate or wooden framing and the vacuum-chamber may communicate directly with the casing-space instead of through an exhaust-box.

Any suitable mechanical device may be 130 employed for operating the forcing-piston.

The fastenings of the sides of the mold-

casing may be of any convenient kind, such as snap-bolts, hasps, or hooks.

We are aware that Patent No. 70,038 to Michael Smith describes an injecting-cylinder lined with clay and supplied with a clay tamping-plug; but such clay plug often proves unsatisfactory from its liability to be detached in large fragments, which have partially or wholly obstructed the passage of the molten metal into the molds. What was needed and which proves in practice to be entirely satisfactory was an infusible substance, whose fibrous composition and tough and close packing qualities made it on the one hand capable of remaining intact under the mere weight of the molten metal, and on the other hand of becoming ruptured without entire separation when to the weight of the metal is added a superimposed external pressure.

We are also aware that Patent No. 407,696 to one of the present applicants, in association with Charles Grasser, describes a packing disk or gasket of asbestos, said disk having a central orifice for the unrestricted passage of the metal when forced upward by the ascent of the piston. In this arrangement the molten metal is supported not by the disk, but by the piston. The disk is not an imperforate one and could not retain the metal even were the apparatus inverted. Its office is merely that of a refractory lining. The imperforate disk of our present improvement, besides acting as a refractory lining, serves to retain the supernatent body of molten metal until the instant when the excess of external pressure enables the metal to rupture and force its way through the disk. The tough and fibrous composition of the asbestos mat causes the ruptured filaments to remain adherent to the mat-body instead of becoming detached in fragments and choking the passage-way, as is the case with such substances as clay or plumbago.

Having thus described our invention, the following is what we claim as new therein and desire to secure by Letters Patent:

1. In a casting apparatus, the combination of a mold-casing, one or more molds therein, a charging or injecting hopper upon said casing, a means of applying pressure above the molten metal in said hopper, a passage through the hopper-floor into said casing, and an imperforate asbestos mat upon said floor, whose substance is such as to temporarily close said passage, but to become ruptured without entire detachment by the application of external pressure to the upper surface of the molten metal, substantially as set forth.

2. In a casting apparatus, the combination of a mold-casing, one or more molds therein, a charging or injecting cylinder above the

such as to close said passage against the weight of the supernatent molten metal and to become ruptured without entire separation on the depression of the piston, in the manner and for the purposes set forth.

3. In a casting apparatus, the combination, with one or more molds, of a hermetical casing therefor, a vacuum-chamber, a passage from said casing to said chamber, a charging or injecting cylinder or hopper, a passage from said hopper into said casing, an imperforate asbestos diaphragm of sufficient substance to temporarily close said passage, and a forcing-piston whose depression ruptures said diaphragm and fills the molds, substantially as set forth.

4. In an apparatus for producing delicate and sharp metallic castings, the combination of a hermetically-closed mold-casing, one or more pairs of molds therein, a forcing-piston, 85 the asbestos facing thereof, a charging-hopper which fits and receives said piston, a passage in the hopper-floor to said mold-casing, an asbestos lining to the hopper-walls, an imperforate asbestos mat that temporarily closes 90 the said passage, and an asbestos bushing to said passage, substantially as set forth.

5. In an apparatus for producing sharp and delicate castings of metals, the described combination of one or more pairs of molds, a 95 hermetically-sealed casing therefor, a charging-cylinder, an asbestos lining to said cylinder, a passage from said cylinder to the interior of said casing and molds, an imperforate asbestos diaphragm which temporarily 100 closes said passage, a forcing-piston which fits said cylinder, and an asbestos facing to said piston, substantially as set forth.

6. In an apparatus for producing sharp and delicate castings in metal, the combination of the base or box 1, one or more superimposed pairs of molds 2, the hinged sides 21, the coping 6, the charging-cylinder 13, supported on said coping and having the screws 13^a and the rabbet 14^a, the disk 11 on the top of said coping, the gate or passage 11' therein, and the asbestos mat or diaphragm 12, whose shape and dimensions are such as to conform to said disk, to engage undersaid rabbet, and to support the uncompressed molten metal, 115 said mat thus serving the several purposes of sealing the junction of the cylinder with the said coping, a non-conducting support and insulator for said molten metal, and a temporary obstruction between the cylinder and the mold-casing, substantially as set forth.

7. In an apparatus for producing delicate and sharp castings of refractory metals, the combination of supporting exhaust-box 1, having a gate or passage 11' in the mold-casing, 125 one or more pairs of molds 2, perforated cop-

formable to said disk and whose substance is such as to support and isolate the molten metal, charging-cylinder 13, having rabbet 14^a and fastening-screws 13^a, asbestos lining 5 15 of said cylinder, asbestos-faced forcing-piston 16, depressing mechanism 17 18 19, hinged casing sides 21, hinged yokes 23, and

clamp-screws 24, the whole being arranged and adapted to operate as set forth.
